US00D853403S

(12) **United States Design Patent** (10) **Patent No.:** **US D853,403 S**
(45) **Date of Patent:** **** Jul. 9, 2019**

(54) **SUPPORT FOR TELEVISION APPARATUS**

(71) Applicant: **Yaqi Lyu**, Shenzhen (CN)

(72) Inventor: **Yaqi Lyu**, Shenzhen (CN)

(**) Term: **15 Years**

(21) Appl. No.: **29/678,780**

(22) Filed: **Jan. 31, 2019**

(51) LOC (11) Cl. **14-02**

(52) U.S. Cl.

USPC **D14/451**

(58) **Field of Classification Search**

EM 002711192-0002 6/2015

Primary Examiner — Katie Jane Stofko

(74) Attorney, Agent, or Firm — JCIP Global Inc.

(57) **CLAIM**

The ornamental design for a support for television apparatus, as shown and described.

DESCRIPTION

FIG. 1 is a perspective view of a support for television apparatus showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate portions of the support for television apparatus and form no part of the claimed design.

1 Claim, 8 Drawing Sheets
